UNITED STATES PATENT OFFICE.

FRANK S. INGOLDSBY, OF ST. LOUIS, MISSOURI, ASSIGNOR TO THE INGOLDSBY AUTOMATIC CAR COMPANY, OF ST. LOUIS, MISSOURI, A CORPORATION OF WEST VIRGINIA.

DUMP-CAR.

1,027,849.

Specification of Letters Patent.

Patented May 28, 1912.

Application filed July 17, 1905. Serial No. 270,018.

To all whom it may concern:

Be it known that I, FRANK S. INGOLDSBY, a citizen of the United States, residing at St. Louis, in the State of Missouri, have invented a certain new and useful Improvement in Dump-Cars, of which the following is a full, clear, and exact description, reference being had to the accompanying drawings.

10 This invention is particularly adaptable for cars of the Ingoldsby type, wherein there is a central longitudinal beam, to the opposite edges of which are pivoted dumping doors adapted to swing downward to discharge the load.

The invention is concerned with the structure of such beam and the door-raising mechanism carried thereby.

It may be summarized as consisting of the features of construction shown in the drawings hereof and herein described and set forth in the claims.

In the drawings, Figure 1 is a cross section through an Ingoldsby dump car embodying the present invention. Fig. 2 is a sectional plan on the line 2-2 of Fig. 1. Fig. 3 is a longitudinal section of the car. Figs. 4 and 5 are end views,--Fig. 4 being from the outside, and Fig. 5 on the line 30 5-5 of Fig. 3.

The central longitudinal beam of the car is a double truss or box girder structure comprising an upper chord A, which is a metal plate of inverted V-shape, lower chords or bracing members, shown as channel beams B-B, and vertical plates C-C riveted to the channel beams and to the ridge plate A. Where these plates C engage the ridge plate they are bent inward and lie 35 along the ridge plate, thus providing more metal for the upper chord. This upper chord is still further reinforced by an angle iron D running lengthwise beneath the ridge plate A. The upper ends of the plates C and this angle D are all securely riveted together. At the lower edge of this double girder are cross braces E, which if desired may be formed by lattice, a plate or separate braces. This longitudinal beam extends 40 to the bolster to which its upper and lower chords and vertical plates are secured, as shown in Fig. 3, where I represents the tension member and I' the compression member of the bolster. The various parts of the center structure pass through the inclined end

floor O and terminate between these members of the bolster.

Connected to the lower chord of the box girder above described at intervals and extending outward therefrom are plates F. 60 These plates are in pairs on each side of the girder and extend outward to the lower portion of the ridge plate A, being connected with the ridge plate and with the girder by angle irons f, f' and suitable rivets. This 65 construction makes a very strong, light and compact beam having the desired slope for discharging the material. It constitutes one of the features of the present invention. In addition to the advantages of strength, compactness and lightness of the above described central beam, it is particularly well adapted for carrying the pivots of the dumping doors and the door raising mechanism. The dumping doors are indicated by G. They have 70 on their underside floor beams g, in the form of angle irons,--the horizontal flange of which is extended at the inner end and bent around onto itself to form a hinge eye at g'. In the same manner the flanges of the clips f' which engage the ridge plate are extended and bent around on themselves to form hinge eyes f''. Through the three eyes thus presented in alignment passes a hinge bolt H. 75

Pivoted on bolts J which pass through 80 the plates F and the angle clips f are operating arms K. These arms are located between suitable pairs of plates F. Each arm extends outwardly and is adapted to have its free end engage the dumping door 85 either on the plate thereof or the angle g beneath the same. These arms K are adapted to be drawn upward by chains L connected with the arms at k and passing upward beneath the ridge plate to a common 90 operating shaft N which is carried in bearing blocks P between the vertical plates C and riveted or bolted to them.

From the above described mechanism, it 95 results that if the shaft N is rotated, the 100 chains are wound thereonto and the arms k are drawn upward, raising the dumping doors. To conveniently rotate the shaft N, I extend it longitudinally beyond the end of the ridge plate and the bolster to which the ridge plate is secured and connect it by suitable gearing with a crank R. As 105 shown, the crank has on it a small pinion R' which meshes with a large gear S' on an intermediate shaft S. On this shaft is 110

a pinion S² meshing with a gear T on the shaft N. The inner end of the shaft S is capable of a slight downward movement to release the gear S' from the pinion R' so that the crank will not be thrown violently around when the doors are dumped. A suitable latch U normally holds the shaft in position with the gears in mesh. The doors may be locked in closed position or released therefrom by any desired mechanism, and the releasing mechanism may automatically operate the latch U to release the shaft S, allowing it to drop sufficiently to move the gear S' out of engagement with the pinion R'. A convenient form of such locking, releasing and latch mechanism is shown in Patent No. 784,265 granted March 7th, 1905, on an application with the present inventor and Joseph R. Bowling.

20 In order to form a suitable stop for the dumping doors when they are dropped, I provide a shoulder k' on the arm K which is adapted to abut the underside of the central beam when the arms are down. The arms thus form not only the means for raising the doors but bumpers by which the impact of them is received as they fall, and whereby they are held in position after they have fallen.

30 Having thus described my invention, I claim:

1. In a dump car, in combination, a beam having an upper chord in the form of a ridge, lower chord members, and longitudinal plates between the upper and lower chord members secured near their upper edges directly to the ridge.
2. A dump car having a beam in the form of a box girder comprising longitudinal members, and a ridge having inclined sides parallel with inwardly bent upper portions of said members, said sides being secured directly to such upper portions, and a bracing member having sides parallel to the sides of the ridge and secured thereto.
3. In a dump car, in combination, a member in the form of a box girder having a ridge along the top thereof engaging the girder plates throughout the length of the ridge, and dumping doors carried by such member.
4. In a dump car, a beam comprising two lower chord members, longitudinal vertical plates riveted thereto and an upper chord member in the form of an inverted V.
5. In a dump car, a structure comprising two lower chord members, longitudinal girder plates riveted thereto, and a sheet metal upper chord member in the form of an inverted V to which said plates are riveted.
6. In a dump car, a beam comprising lower chord members, longitudinal vertical plates riveted thereto, an upper chord member in the form of a ridge, the vertical

plates being bent inwardly diagonally beneath such ridge, and secured thereto to reinforce the same.

7. In a dump car, a beam having an upper chord member in the form of a ridge, longitudinal vertical plates bent inwardly diagonally beneath such ridge, and a reinforcing angle extending beneath along the ridge and riveted to the inturned ends of the vertical plates and to the ridge. 75

8. In a dump car, the combination of a ridge forming an upper chord, lower chord members beneath the ridge, longitudinal plates connecting the ridge with such members, and cross members connecting the lower chord members and the ridge. 80

9. The combination of a ridge plate, a pair of longitudinal vertical plates beneath it and riveted to it, strengthening members secured to said plates, and cross plates connected to said plates and to the ridge plate. 85

10. The combination of a ridge, a pair of longitudinal vertical plates beneath it and riveted to it, a pair of strengthening members in the form of rolled structural shapes riveted to said plates, and cross members connected to said shapes and to the ridge. 90

11. In a dump car, the combination of a ridge, continuous longitudinal bracing means beneath it, transverse members connecting said bracing means with the ridge, such connecting members including cross plates and angle members riveted to the cross plates and to the ridge and the bracing means. 95

12. In a dump car, the combination of a ridge, bracing means beneath it, cross plates connecting said bracing means with the ridge, such connection including angle members whose flanges are extended downwardly and bent back on themselves to form hinge eyes, and a dumping door having aligned hinge eyes, and a hinge pin passing through said eyes. 100

13. A dump car, the combination of a ridge, bracing beneath the same, cross plates connecting the bracing with the ridge, dumping doors pivotally supported by such structure, a central longitudinal shaft beneath the ridge, and mechanism operated thereby and adapted to raise the dumping doors on both sides. 110

14. In a dump car, the combination of a metal ridge, a metal box girder beneath the same and including longitudinal plates connected to the ridge thereof, cross plates between the outer side of the box girder and the ridge, dumping doors pivotally supported by such structure, and pivoted arms carried by the structure adapted to engage the dumping doors and means for raising such arms. 120

15. In a dump car, the combination of a ridge, dumping doors pivoted near the edges thereof, arms for raising such doors, a com- 125

- mon rotatable operating shaft located beneath the ridge, and means connecting said shaft with the arms. 16. In a dump car, the combination of a 5 pivoted door, an arm adapted to engage and raise the same, an operating shaft, and a chain connected at one end to the shaft and at the other to the arm. 17. A dump car, the combination of a 10 ridge, dumping doors pivoted near the edges thereof, a common operating shaft located beneath the ridge, and arms pivoted upon a rigid support operated by said shaft to simultaneously close the doors. 18. In a dump car, the combination of a 15 ridge, dumping doors pivoted near the edges thereof, arms for raising such doors, a common operating shaft located beneath the ridge, chains beneath the ridge connected 20 at their upper ends to said shaft and at their lower ends to said arms. 19. In a dump car having inclined ends and an inverted V-shaped central beam, the combination with dumping doors hinged 25 near the opposite edges of said beam, of a common operating shaft located beneath the ridge of the beam and extending longitudinally beneath the inclined end of the car, means outside of such inclined end for 30 rotating said shaft, and means beneath the ridge plate for communicating motion from the shaft to the doors. 20. In a dump car having inclined ends and a central ridge beam, the combination 35 with dumping doors hinged near the opposite edges of said beam, a common operating shaft located beneath the ridge of the beam and extending longitudinally beneath the inclined end of the car, means for 40 rotating said shaft, arms pivoted to the beam, and adapted to engage the doors, and flexible mechanism connecting said arms with said shaft. 21. In a dump car, the combination with 45 a dumping door, a pivoted raising arm therefor, and an abutment for the raising arm independent of its pivot. 22. In a dump car, the combination of a 50 dumping door, a pivoted arm adapted at its free end to engage the same to raise the door, means for raising the arm, and a shoulder on said arm which by engaging an abutment forms a bumper for the door. 23. In a dump car, the combination of a 55 ridge plate, a longitudinal strengthening structure beneath the same, a pair of arms pivoted to such structure, shoulders on the arms adapted to abut such structure when the arms are down, a longitudinal shaft beneath the ridge plate, means connecting same with said arms, and dumping doors adapted to be raised by said arms. 24. In a dump car, the combination of a 60 pair of longitudinal plates the lower portion of which is vertical and the upper por- 70 tion of which is inclined inwardly, a ridge of sheet metal resting on such inwardly inclined portions and riveted thereto, and lower chord members in the form of longitudinal flanged shapes riveted to said plates near their lower edges. 25. In a dump car, the combination of a pair of girder plates having inclined upper portions and reinforced lower portions, a 75 surmounting roof riveted to such upper portions, and braces riveted to the girder plates extending to the sides of the roof. 26. In a dump car, the combination of a pair of longitudinal plates, the lower portion of which is vertical and the upper portion of which is inclined inwardly, a sheet metal ridge surmounting and riveted to such inwardly inclined portions, lower chord members in the form of flanged shapes riveted to said plates near their lower edges, 80 and cross bracing members between the outer sides of said plates and the overhanging portion of the ridge. 27. In a dump car, the combination of a pair of bolsters, a ridge, a pair of vertical 85 longitudinal plates beneath the ridge and secured to it, said plates and said ridge both extending from bolster to bolster and secured to the bolsters. 28. In a dump car, the combination of a pair of bolsters, a ridge, a pair of vertical longitudinal plates beneath the ridge and secured to it, said plates and said ridge both 90 extending from bolster to bolster and secured to the bolsters, and inclined end floors between the bolsters, said plates and ridge 95 passing through the end floors. 29. The combination of a pair of bolsters, inclined end floors between the bolsters, a longitudinal structure comprising a pair of 100 longitudinal plates extending from bolster to bolster, a surmounting ridge and cross braces between the longitudinal plates and the ridge. 30. The combination of a pair of bolsters, 105 a pair of longitudinal plates extending from bolster to bolster, a ridge surmounting said plates and secured to them, cross braces between said plates and the overhanging portion of the ridge, stiffening members extending along said longitudinal plates, and dumping doors hinged to such structure adjacent to the lower edge of the ridge. 31. The combination of a pair of bolsters, inclined end floors between the bolsters, a longitudinal structure comprising a pair of 110 longitudinal plates extending from bolster to bolster, and a surmounting ridge to which said plates are connected extending from bolster to bolster. 32. The combination of a pair of bolsters, inclined end floors between the bolsters, a longitudinal structure comprising a pair of 115 longitudinal plates extending from bolster to bolster, a surmounting ridge to which 120 said plates are connected extending from bolster to bolster. 125 65 130

said plates are connected extending from bolster to bolster, and stiffening means for the lower portions of said plates.

33. The combination of a pair of bolsters, 5 inclined end floors between the bolsters, a longitudinal structure comprising a pair of longitudinal plates extending from bolster to bolster, a surmounting ridge to which said plates are connected, stiffening means for 10 the lower portions of said plates, and transverse means for bracing the overhanging portion of the ridge, and the lower portion of the longitudinal plates.

34. The combination of a pair of bolsters, 15 inclined end floors between the bolsters, a longitudinal structure comprising a pair of longitudinal plates extending from bolster to bolster, a surmounting ridge to which said plates are connected, stiffening means for 20 the lower portions of said plates, transverse braces between said plates and the overhanging portion of the ridge, bracing means between the two plates, and dumping doors hinged adjacent to the lower edge of the 25 ridge.

35. The combination with the bolsters, of center sills extending from bolster to bolster; draft plates on the outer sides of the bolsters, inclined end floors, a shedding 30 ridge carried by the center sill plates and extending from bolster to bolster, and dumping doors carried by such center structure.

36. In a dump car, the combination of a 35 ridge forming an upper chord, lower chord members beneath the ridge, plates connecting the ridge with such members, cross members between the outer sides of the plates and the overhanging portion of the ridge, 40 and raising mechanism carried by such structure.

37. In a dump car, the combination of a ridge forming an upper chord, lower chord members beneath the ridge, plates connecting 45 the ridge with such members, cross members between the outer sides of the plates and the overhanging portion of the ridge, and a raising arm and an operating shaft carried by such structure.

50 38. In a dump car, the combination of a ridge forming an upper chord, lower chord members beneath the ridge, plates connecting the ridge with such members, cross members between the outer sides of the plates and the overhanging portion of the ridge, and a raising arm carried by such structure, a rotatable shaft, and a chain connecting the shaft with the arm.

39. In a dump car, the combination of a 60 ridge forming an upper chord, lower chord members beneath the ridge, plates connecting the ridge with such members, cross members between the outer sides of the plates and the overhanging portion of the ridge, 65 and doors hinged adjacent to the lower

edge of the ridge, and raising mechanism for the doors.

40. In a dump car, the combination of a ridge forming an upper chord, lower chord members beneath the ridge, plates connecting the ridge with such members, cross members between the outer sides of the plates and the overhanging portion of the ridge, doors hinged adjacent to the lower edge of the ridge, raising arms for the 75 doors, and means for operating said arms.

41. In a dump car, the combination of a ridge forming an upper chord, lower chord members beneath the ridge, plates connecting the ridge with such members, cross 80 members between the outer sides of the plates and the overhanging portion of the ridge, doors hinged adjacent to the lower edge of the ridge, arms for raising said doors, a rotatable shaft and flexible members connecting the shaft with said arms.

42. In a dump car, the combination of a ridge, a pair of parallel plates beneath the ridge and connected with it, two parallel plates extending transversely from the 90 outer sides of the plates first mentioned to the overhanging portion of the ridge.

43. In a dump car, the combination of a ridge, a pair of parallel plates beneath the ridge and connected with it, two parallel 95 plates extending transversely from the outer sides of the plates first mentioned to the overhanging portion of the ridge, and raising arms located between the parallel plates last mentioned.

44. In a dump car, the combination of a ridge, a pair of parallel plates beneath the ridge and connected with it, two parallel plates extending transversely from the outer sides of the plates first mentioned to 105 the overhanging portion of the ridge, raising arms located between the parallel plates last mentioned, and doors hinged adjacent to the lower edge of the ridge adapted to be engaged by said arms.

45. In a dump car, the combination of a ridge, dumping doors pivoted near the edges thereof, arms for raising such doors, and a rotatable shaft located beneath the 110 ridge and connected with said arms.

46. In a dump car, the combination of a dumping door, a pivoted arm adapted to raise the door, means for raising the arm, and an abutment which said arm may engage when down whereby the arm may 120 form a bumper.

47. In a dump car, the combination of a ridge, a pair of longitudinal vertical plates connected to the ridge near their upper ends, pairs of transverse plates between the outer sides of the longitudinal plates, and the overhanging portion of the ridge, and dumping doors hinged adjacent to the outer 125 ends of said pairs of transverse plates.

48. In a dump car, the combination of a 130

ridge, a pair of longitudinal vertical plates connected to the ridge near their upper ends, pairs of transverse plates between the outer sides of the longitudinal plates, and 5 the overhanging portion of the ridge, dumping doors hinged adjacent to the outer ends of said pairs of transverse plates, and door raising arms between said transverse plates hinged near the inner ends of the transverse 10 plates.

49. In a dump car, the combination, with a pair of vertical longitudinal plates, a ridge secured to the said plates at the upper ends of said plates, a shaft located between 15 the said vertical plates and beneath the ridge, doors pivoted to said ridge, and operative connections between the said shaft and the said doors.

50. In a dump car, the combination, with 20 a pair of vertical longitudinal plates, of a ridge secured to said plates, cross members extending between the said vertical plates, a shaft journaled in said cross members, doors pivoted upon the said ridge, and operative connections between the doors and 25 the said shaft.

51. In a dump car, the combination, with a pair of vertical longitudinal plates, of 30 an inverted V-shaped ridge surmounting said plates and secured thereto, stiffening members arranged in pairs and secured to the longitudinal plate and to the lower edge

of the ridge, arms extending between the said stiffening members and pivoted upon said members, doors pivoted upon the lower 35 edge of the ridge, and means for raising the said arms.

52. In a dump car, the combination, with a central beam, of an inverted V-shaped ridge surmounting said beam, a pair of 40 stiffening plates spaced apart secured to the central beam and to the lower edge of the inverted ridge, an arm extending between the said stiffening plates and pivoted thereupon, a door pivoted upon the said ridge 45 coöoperating with the arm, and means for raising the said arm.

53. In a dump car, the combination, with a central beam, of an inverted V-shaped ridge surmounting said beam, stiffening 50 plates arranged in pairs and secured to the central beam and to the lower edges of the ridge, arms pivoted upon the said stiffening plates and extending between the same, doors pivoted upon the lower edges 55 of the ridge with which the arms coöperate, and means for operating the said arms.

In testimony whereof, I hereunto affix my signature in the presence of two witnesses.

FRANK S. INGOLDSBY.
